UNITED STATES PATENT OFFICE.

GEORGE S. BARSUMIAN, OF OAK PARK, ILLINOIS.

METHOD OF CLEANING RUGS.

Application filed October 28, 1918. Serial No. 259,969.

To all whom it may concern:

Be it known that I, GEORGE S. BARSUMIAN, a citizen of the United States, and a resident of the village of Oak Park, in the county 5 of Cook and the State of Illinois, have invented certain new and useful Improvements in Methods of Cleaning Rugs, of which the following is a specification, reference being had to the accompanying drawings, forming a part thereof.

This invention relates to a method of cleaning rugs or other fabric and to means for supporting and handling them during the process, designed to avoid undue strain 15 or wear on the fabric. It consists in the several steps or operations and of the various features and elements of construction hereinafter described and shown in the drawings as indicated by the claims.

20 In the drawings:

Figure 1 is a somewhat diagrammatic elevation of an apparatus embodying this invention.

Figure 2 is a detail section on a larger 25 scale taken as indicated at line, 2—2, on Figure 1.

Figures 3, 4 and 5 are diagrammatic sectional views of the rug-supporting drum showing the arrangement thereon of various 30 sizes of rugs.

Figure 6 is a detail section taken in a plane transverse to the axis of the rug-supporting drum and showing a fastening device for securing the ends of the rugs to 35 the drum.

Figure 7 is a detail section taken similarly to Figure 6 showing a modified form of fastening means.

Figure 8 is a detail section taken similarly 40 to Figures 6 and 7, showing another modification of the fastening device.

Figure 9 is a detail section illustrating 45 still another alternative form of fastening device.

The method of cleaning rugs which is contemplated by this invention and which 50 may be applicable to the cleaning of certain other fabrics consists of several steps or operations, namely, a thorough sweeping of the surface, preferably within a housing or enclosure of some kind for loosening mechanically as much of the dirt as possible, second, the removal of this dirt, preferably by the force of a spray of water directed against the rug and arranged to 55 clear the housing or receptacle of the dirt

thus collected; third, a thorough washing of the fabric with soap and water, and, if desired, with suitable chemicals; fourth, a complete rinsing in clear water; fifth, removal of most of the moisture by centrifugal action, the rug being arranged as a cylinder and revolved about its axis rapidly, and, finally, the completion of the drying process in a warm dry atmosphere. Ordinary 60

methods now in use involve unnecessarily harsh treatment of the rug surface in the sweeping operation and undue strain upon the fibers, especially in the washing operation, as where the rug is merely thrown 65 into a vat or tank of cleaning fluid and agitated therein with resulting creasing and crumpling; and to avoid such undue wear or strain, I prefer to mount the rug at the beginning of the process on a carrier in the 70 form of a drum, 1, securing the rug right side out to the cylindrical surface of such drum by any suitable fastening device. Preferably this operation of securing the 75 rugs to the drum, 1, may be performed at 80 some point such as indicated at A in Figure 1 outside the vat or tank in which the cleaning operation is to be performed, and the drum may then be moved into such tank as by rolling it upon its projecting journals, 2, 85

along a track, 3, whose folding end portion, 4, will register with a vertically movable section, 5, within the tank or housing, 6. As shown, said tank is provided with side walls hinged at 7 and 8, for folding down 90 to form an opening to admit the drum, 1, and the track sections, 5, of which there is one at each end of the tank are slidably carried for vertical adjustment upon the guides, 9, and arranged to be operated by 95 cables, 10, passing around a suitable windlass, 11. At the middle of its length, each section, 5, carries an upwardly-open bearing or cradle, 12, to receive the journals, 2, of the drums, 1, and as shown in Figure 2, 100 upon lowering the drum on its supporting sections, 5, to working position in the tank, 6, the journal, 2, will come into alignment with a driving shaft, 13, carrying a drive pulley, 14, and a square socket in the journal, 105 2, indicated at 15, may be operatively engaged by the squared coupling member, 16, which is slidably carried in the shaft, 13.

The hinged side walls, 17, being now 110 closed and power being applied to the pulley, 14, the drum, 1, is rapidly rotated in the housing and the sweeping operation is

carried out by contact of the surface of the rug, B, on the drum, 1, with a brush, 18, removably fixed in position extending longitudinally of the drum, as shown in Figure 1 and with comparatively long straws or bristles which are flexible enough to engage the rug softly rather than harshly. The so-called tank, 6, includes a complete housing for the drum during this operation so that the dust and dirt loosened from the rug by this sweeping is confined to the housing. After a suitable period of this treatment, the dust in suspension in the atmosphere within the housing, 6, as well as the dirt which has been merely loosened from the rug's surface but not actually removed therefrom is collected by a sudden downpour of water in a finely divided spray coming through the perforated top wall, 19, of the housing, which forms the bottom wall of a reservoir, 20, of limited capacity having a large supply pipe, 21, leading thereto from an adequate supply of water. It may be understood that no water is admitted to the reservoir, 20, until it is wanted for collecting the dust from the interior of the housing, 6, but that when it is thus needed it is supplied in large quantities and suddenly through the pipe, 21, so that it is immediately distributed over the entire area of the perforated wall, 19, and thus descends almost simultaneously throughout the chamber, 6. Preferably the rotation of the drum, 1, is continued during this portion of the process to assist the water in removing the loose dirt particles from the rug's surface and to insure equal treatment for the entire area. A drain pipe of large capacity leading from the bottom of the tank, 6, will conduct away the water as fast as it enters the tank so that in a few moments there will be a complete flushing of the tank and a complete removal of all the loose dust and dirt therefrom. Such drain pipe is indicated at 22 in Figure 1, and is provided with any suitable valve or plug, not shown.

Now by shifting the belt upon the cone pulley, 14, or by other suitable means, the speed of the drum may be reduced for the washing operation and wash water introduced into the lower portion of the tank, 6, to some level below that of the hinges, 7, as through the supply pipe, 23, and soap or other washing compound may be introduced to form the desired cleaning solution. Then for a suitable period the drum is slowly revolved thus carrying the rug through this washing solution permitting the solution to thoroughly permeate the rug and loosen and remove any remaining dirt therein. At intervals the hinged cover, 17, or the similar hinged cover, 24, at the opposite side of the housing may be opened for inspection of the rug to determine how long the washing operation shall be continued

and when it is satisfactorily completed the washing solution may be drained off through the drain, 22, or other similar drain leading inward to a waste pipe or to a reservoir in which the washing solution may be preserved if desired. Clear water is then introduced as through the supply pipe, 23, and by continued rotation of the drum in the tank, 6, the cleaning solution will be gradually rinsed out of the rug or other fabric being treated and the rinse water may be drained off as at 22. Obviously the rinsing operation may be repeated one or more times if desired. If other cleaning treatment is desired, a suitable cleaning solution such as naphtha or gasoline may be introduced into the tank, 6, and the drum, 1, revolved to subject the entire surface of the rug to the action of such solution and when such action is complete the solution may be drained off at 22.

The cleaning operations being completed it is possible to remove nearly all the water or other moisture remaining in the body of the rug or fabric, B, by merely revolving the drum rapidly in the tank, 6, so that centrifugal force acting upon the liquid will cause it to fly out against the walls of the tank, 6, and drain out through the pipe, 22. This will leave only a minute quantity of moisture remaining in the body of the fabric. Then by operating the windlass, 11, the track sections, 5, may be elevated to register with the folding end portions, 25, of a track, 26, along which the drum, 1, resting on its journals, 2, may be rolled into a suitable drying room or compartment at a position indicated at C on Figure 1, where by the action of heat the slight remaining moisture will be completely evaporated and the rug may be removed from the drum, 1, ready for use again.

Preferably the rug, B, will be secured to the cylindrical surface of the drum, 1, by engagement of its extreme end portions extending longitudinally of the drum by suitable fastening means for clamping these end portions in position. Necessarily the end portions, B¹, will thus be covered during the cleaning operation; they will therefore be completely cleaned by hand before the rug is applied to the drum, 1, at A, so that only the exposed area of the rug remains to be cleaned when it enters the tank or housing 6.

To avoid any form of fastening means which would project beyond the cylindrical surface of the rug, B, as applied to the drum involves constructing the drum, 1, with longitudinal grooves and securing the end portions of the rug in such grooves below the general cylindrical outline. Such form of fastening device is indicated at Figure 6 in which a fragment of the drum is shown as constructed of a circular web, 27, whose

rim is formed with notches, 28, into which there are set longitudinally-extending bars, 29, in pairs with inclined opposing faces, 30. A cylindrical locking bar, 31, is arranged to be drawn down between said inclined faces, 30, by means of clamping bolts, 32, engaging the web or frame member, 27; in a drum of considerable length there may be a series of such reinforcing and supporting circular frames, 27, disposed at intervals along the axis of the drum with clamping bolts, 32, engaging each of such frames, 27, for distributing the clamping action along the entire length of the drum and adequately securing the end portions, B^1 , of the rug between the member, 31, and the surface, 30. It may be noted that if the circumference of the drum, 1, is substantially equal to the length of the rug, B, both ends of the rug may be secured in the same groove, 28, by the same fastening member, 31, as shown in Figure 6 and also in Figure 3. If the length of the rug should be somewhat less than the circumference of the drum separate fastening members, 31, may be employed in separate grooves, as shown in Figure 4; and if relatively small rugs are applied to the drum, 1, for cleaning, several such rugs may be assembled on its surface as indicated in Figure 5, a single fastening element, 31, being employed for securing the contiguous ends of adjacent rugs, B^2 and B^3 , respectively, while separate fastening means, 31, are used to secure their opposite ends if said ends do not happen to come to the same groove on the drum.

A modified form of fastening means is illustrated in Figure 7 in which the groove or space between adjacent bars, 33, of the form shown is wide enough to admit two cylindrical clamping bars, 34. The clamping bolts, 35, are quite rigidly guided in long threaded sockets, 36, so that either end, B^1 , of the rug, B, may be secured independently of the other end as the clamping bar, 34, is pulled down by its bolts, 35, against the surface, 37, of the fixed bars, 33, which surface is curved and inclined toward the bolts, 35. In addition to converging toward the bolts, 35, the opposite surfaces, 37, also converge with respect to each other, so that after each end, B^1 , of the rug has been separately secured by one of the clamping bars, 34, any further tightening of the bolts, 35, will cause the bars, 34, to wedge against each other between the opposing surfaces, 37, and increase the security of the fastening.

Figure 8 shows a rather different form of securing means which involves forming the fixed longitudinal bars, 38, with opposing grooves, 39, to receive the end portions, B^1 , of the rug B. The clamping device consists of two flat bars, 40, hinged together at their adjacent edges and operating as a

toggle with their opposite edges forcing the ends, B^1 , of the rug, into the grooves, 39. Clamping bolts, 41, distributed at suitable intervals along the hinge axis of the toggle and provided with suitable washers, 42, overlying the hinge joints and crowding plates, 43, underlying the toggle tend to straighten out the members, 40, into clamping position. In some cases the toggle action may be dispensed with and a simple holding strip, 44, with a reduced and tapered end portion, 45, may be inserted longitudinally between the ends, B^1 , of the rug for holding them in the grooves, 39, as shown in Figure 9.

It may be understood that the brush, 18, removably mounted in the housing, 6, may remain in position if desired during the washing process, or may be removed immediately after the sweeping is finished. It may also be understood that, if preferred, the washing solution may remain in the housing, 6, and the drum carrying the rug, B, may be removed to a second tank or housing for the rinsing operation. The centrifugal drying may then be effected in said second housing after draining off the rinse water or by further removal to a third housing or enclosure. This drying operation may be carried out without draining off the rinse water from its container.

It is a feature of my method that all operations except the final drying are carried on by rotation of the rug-carrying drum within an enclosing housing, but not necessarily within the same housing for all the process. A plant of moderate size, however, will be well equipped if provided with a single tank or housing, 6, in which the different steps or operations are carried on successively, so that a single machine will thus perform the work for which three or four separate machines are now ordinarily required. Further advantages of the method are that the rug is subjected to no harsh treatment either in the washing process or the removal of the cleaning liquid (which is ordinarily effected by a pressure wringer) and by reason of the uniformity of the treatment over the entire rug surface and especially as the effect of the centrifugal removal of the water the nap is given a much better appearance as well as being more thoroughly cleaned.

I claim:

1. The part of a method of cleaning a rug which consists in feeding its nap surface against and past yielding brushing means for gently removing dust therefrom; confining such dust to the vicinity of the rug; collecting the dust by means of a finely divided shower of liquid released from above the rug and distributed over the entire transverse area adjacent the rug, said rug itself being disposed in the path of such

shower for removal of the loosened dust on its surface; and draining away the liquid and the dust collected thereby.

2. The part of a method of cleaning a rug which consists in feeding its nap surface against and past yielding brushing means for gently removing dust therefrom; confining such dust to the vicinity of the rug; collecting the dust by means of a finely divided shower of liquid released from above the rug and distributed over the entire transverse area adjacent the same while revolving the rug in cylindrical form about the axis of such form in the path of the shower for removal of the loosened dust on its surface; and draining away the liquid and dust collected thereby.

3. The complete method of cleaning a rug which consists in addition to that set out in claim 1 in moving the rug slowly through a path of cleansing liquid by revolving it in

cylindrical form about the axis of such cylinder; similarly moving the rug through a rinsing path; drying the rug by revolving it rapidly about the said axis of its cylindrical form with its nap surface disposed outwardly to effect centrifugal removal of the moisture; and finally completing the drying process in the presence of a mild degree of heat.

4. In the process of washing a rug, the method of removing surplus moisture therefrom and raising the nap which consists in revolving the wet rug in cylindrical form about the axis of such form with its nap surface disposed outwardly to effect centrifugal removal of the moisture and radial disposal of the nap fibers.

In testimony whereof, I have hereunto set my hand at Chicago, Illinois, this 23d day of October, 1918.

GEORGE S. BARSUMIAN.
